(57) **CLAIM**

I claim the ornamental design for the floatable water monitor, as shown and described.

DESCRIPTION

FIG. 1 is a right side view of a floatable water monitor showing my new design;

FIG. 2 is front view thereof;

FIG. 3 is a left side view thereof;

FIG. 4 is a rear view thereof;

FIG. 5 is a top view thereof;

FIG. 6 is a bottom view thereof;

FIG. 7 is a perspective view thereof;

FIG. 8 is right side view thereof, with the bottom portion extended;

FIG. 9 is a front view thereof;

FIG. 10 is a left side view thereof;

FIG. 11 is a rear view thereof;

FIG. 12 is a top view thereof;

FIG. 13 is a bottom view thereof; and,

FIG. 14 is a perspective view thereof.

The broken line showing is included for the purpose of illustrating and forms no part of the claimed design.
